UNITED STATES PATENT OFFICE

152,254

DESIGN FOR A HOLDER FOR EYEGLASSES

Michael S. Gallo, Racine, Wis.

Application April 30, 1947, Serial No. 138,697

Term of patent 14 years

(Cl. D57—1)

To all whom it may concern:

Be it known that I, Michael S. Gallo, a citizen of the United States, residing at Racine, in the county of Racine and State of Wisconsin, have invented a new, original, and ornamental Design for a Holder for Eye Glasses, of which the following is a specification, reference being had to the accompanying drawing, forming part thereof.

Figure 1 is a perspective view of a holder for eye glasses, showing my new design; and

Figure 2 is a cross-sectional view thereof taken on the plane of line 2—2 in Figure 1.

The outline of a pair of spectacles shown in broken lines in Figure 1 is for illustrative purposes only.

I claim:

The ornamental design for a holder for eyeglasses, as shown and described.

MICHAEL S. GALLO.
